IGNITION APPARATUS

Harry B. Holthouse, Chicago, Ill.

Application April 9, 1938, Serial No. 201,057

19 Claims. (Cl. 123—148)

This invention relates to ignition systems and has been illustrated as embodying various new structures as well as novel circuit features previously invented by me.

5 In my copending application Serial No. 741,610, filed August 27, 1934, (now Patent No. 2,117,422, issued May 17, 1938) I have disclosed certain new ignition circuits which are characterized in part by the addition of a high frequency booster unit 10 to the conventional ignition circuit. Ignition systems built in accordance with that invention have proved very advantageous. As an indication of the value of such a system, it may be noted that the spark generated thereby will jump a very 15 much wider gap than will the spark of a conventional ignition system. Furthermore, the high frequency characteristics result in a very pronounced tendency to generate ozone, which is beneficial in producing ignition. It so happens, 20 however, that both of these features, though very advantageous, make the voltage hard to handle. The higher voltage, or in general the tendency to jump wider gaps, means that extra precautions must be taken in adequately insulating the various 25 terminals and contacts. The readily moldable insulating materials such as "Bakelite" can have their surfaces transformed to a relatively conductive material by a current passing along the 30 surface, and the prevention of this is very important. The ozone greatly aggravates the problem since it is chemically a very effective oxidizing agent, being ionized or separated from its molecular form to an atomic form which is very 35 unstable, tending to combine with the first available substance.

A very important object of the present invention is accordingly to produce apparatus which will handle the high voltage and high frequency currents with complete satisfaction. Various 40 departures from prior practice are adopted in accomplishing this object. The terminals are adequately insulated, sometimes by the aid of grooves which elongate the surface path between the terminals. The distributor contacts are preferably 45 adequately separated by similar grooves which, however, must be reduced to a very narrow width in the direction of rotation of the rotating contact to permit this contact to pass over them readily. There are preferably a plurality of the narrow air 50 gaps thus formed between each pair of the stationary contacts. The distributor also preferably includes provision for ventilation to avoid any high concentration of ozone.

Under some circumstances the high frequency boosting unit works best when it is located imme-

dately adjacent to the distributor so that the high frequency circuits may be of minimum length. Accordingly, another object of the invention is to provide satisfactory constructions for mounting the booster unit directly on the distributor unit. It should be noted that some of the constructions for this purpose were disclosed in my prior application mentioned and the present application is therefore in part a continuation thereof in the nature of a division.

10 In other instances it is more desirable to include the boosting unit as a part of the main ignition coil unit, particularly when the combined units are to be substituted for the conventional coil already in use on an internal combustion engine. One object of the invention is therefore to provide a satisfactory structure for this combination.

Another object of the invention is to provide the booster unit, or at least the secondary coil 20 thereof, as a replaceable unit including a molded insulating housing. This secondary coil is the coil most likely to fail upon those rare occasions when something fails, and the ability to replace it readily is very advantageous.

The advantages and objects of the invention will be made more apparent by the following description and by the drawings, in which:

Fig. 1 is a sectional view of one combined distributor and booster coil unit constructed in accordance with this invention.

Fig. 2 is a plan view of the structure shown in Fig. 1 with the top removed therefrom and a portion of the rotor broken away.

Fig. 3 is a diagrammatic drawing of the circuit 35 for which the structure of Figs. 1 and 2 and some of the modifications shown in other figures are intended.

Fig. 4 is a sectional view of one preferred form 40 of the combination coil unit.

Fig. 5 is a sectional view of a modified form of distributor and booster coil combination.

Fig. 6 is a perspective view partly broken away 45 of the rotor of Fig. 5.

Fig. 7 is a modified form of the combination coil unit, in which a pair of condensers and a kick coil are also included.

Figs. 8 to 10 illustrate other modified forms 50 of combination distributor and high frequency coil, Fig. 8 showing one form adapted for use with the conventional spark coil, Fig. 9 showing a similar form with separable parts, and Fig. 10 showing a form similar to that of Fig. 8 but adapted for use with a mere kick coil.

Fig. 14 is a plan view of the supporting partition wall in the structure of Fig. 12.

10 Although this invention may take numerous forms, only a few have been chosen for illustration. All of the forms of the apparatus have been illustrated as specially adapted to handle very high voltages having high frequency characteristics. Figs. 1 and 2 illustrate a combined timer, distributor, and high frequency booster coil 15 having this qualification.

Since the timer does not need to handle such unusually high voltages, it may be of conventional form and has been indicated by the spring contact arm 10, contacts 11 and cam 12 mounted 20 on the shaft 13 which would of course be driven in timed relation with the motor, usually at half speed. Above the timer contact 11 the shaft 13 passes through a distributor block 14 having 25 therein a distributor cavity 16. On its upper end the shaft 13 carries a distributor rotor 17 which has a rotating contact 18 which may be spring-urged as indicated against the stationary contacts 19. The rotating contact 18 or brush, as it 30 may be called for convenience, is also connected through tube 21 and axial spring contact 22 with a contact 23 through which the high voltage current is supplied to the distributor to be distributed to the various spark plugs, which are of 35 course connected to the stationary contacts 18 through wires extending into terminal sockets 24. These wires may be held in place and in contact with studs formed on the stationary contacts 18 by means of screws 25 which may be threaded into a bushing within the body 14 if preferred. 40 Of course, there are many other satisfactory ways of connecting such wires.

The contact 23 is carried by the bottom 26 of a housing 27 which encloses a high frequency booster unit HF. This unit includes a primary 45 winding 28 connected to the terminals 29 and a secondary winding 31 connected at one end to the contact 23 and at the other end to a terminal 32 formed in a socket 33 which is adapted to receive the lead wire from the conventional ignition 50 coil. A pair of condensers 34 and 35 are suitably mounted in any convenient position as on the metallic housing 36 of the timer unit. The advantage of this location is of course that the condensers will thus be grounded through the 55 housing 36 to the engine block.

The ignition system for which the structure of Fig. 1 is particularly adapted is seen in Fig. 3. The battery 41 may as usual be connected to ground and to a conventional ignition coil LF 60 including the primary winding 42 and the secondary winding 43. This coil may be spoken of as the low frequency coil. The primary winding 42 will be connected to ground through the timer contacts 11 which will be opened by the 65 cam 12 at the time ignition is desired. This will interrupt the flow of current in the primary winding 42 so that there will immediately be a high induced voltage in the secondary winding 43 and a high self-induced voltage in the primary winding 42. This latter voltage may for convenience be called the kick voltage. To keep the kick voltage from immediately sparking across the gap formed by the contacts 11, it has been customary 70 to provide a condenser 35 across these contacts so that the kick voltage would be absorbed by the

condenser 35. This condenser charge has always been wasted before my invention and, in fact, it has been worse than wasted since it would usually be discharged and thus produce a spark across the timer contacts 11 as they subsequently approached one another in closing. This spark was of course mainly, if not entirely, unidirectional, and the result was that the contacts 11 were eventually pitted by it or otherwise injured. 10

According to my invention disclosed in my co-pending application previously mentioned, the kick voltage instead of initially being merely held in condenser 35 is discharged through a low frequency primary winding or coil 28 and a second 15 condenser 34 which is also grounded. The coil 28, the condenser 34, and the timer contacts 11 form a high frequency oscillating circuit so that a high frequency spark jumps across the contacts 11 instead of a low frequency spark. It has been 20 found that this high frequency spark does not pit the contacts 11. This alone is a great advantage of my ignition system but it is not the principal advantage.

The principal advantage involves the use of the 25 high frequency secondary winding 31 which is in inductive relationship with the primary winding 28. This winding 31, it will be noted, is interposed in series between the low frequency secondary winding 43 and the distributor rotor 17. 30 The result is that the high voltage induced by induction between winding 28 and winding 31 boosts the voltage of winding 43 so that a very high voltage is impressed across the gaps 44, representing the spark plugs. Furthermore, this 35 voltage and the resulting spark have pronounced high frequency characteristics which are also advantageous. The winding 28 facilitates the discharge of condenser 34 so that the discharge, and the voltage boost, take place during the voltage surge of winding 43. It is thus seen that the kick voltage of coil 42 instead of being wasted and injuring the contacts 11 is utilized to produce better ignition and is changed so that it will not injure the contacts. 40

From the foregoing it will also be evident, however, that the voltage supplied to the contact 23 and which must be handled by the rotor 17 is not only a very high voltage but is also a high frequency voltage. Great care should therefore be 50 taken to prevent flashing-over either between the brush 18 and ground, represented by shaft 13, or between one stationary contact 19 and another. Flashing-over between the brush 18 and the shaft 13 is effectively prevented by means of 55 concentric grooves 51 formed in the bottom of the rotor and the bottom of the distributor cavity 16. These concentric grooves serve to greatly lengthen the surface paths along the respective insulating members. It should be observed that 60 it is extremely important to prevent such flash-overs with some materials such as "Bakelite" which are rendered relatively conductive by such a flash-over so that subsequent flash-overs occur more and more readily, or a constant voltage 65 leakage occurs.

The tendency toward flashing-over between stationary contacts 19 is greatly increased by the rotating brush 18. In the first place, this brush may wipe some metallic particles from the stationary contact 19 along the surface of the insulating housing 14. In the second place, if the sparking current continues as the brush 18 leaves the contact 19, it will naturally spark 70

between them along the surface of the insulating housing 14 and transforms this housing into a relatively good conductor along the path of the spark. It should be noted that at the present time housings of material such as "Bakelite" which can be thus transformed are almost necessarily used because of the ease and accuracy with which such materials can be formed by molding. To prevent such flash-overs the present invention contemplates a series of slots 53 formed in the wall of the cavity 16 between the stationary contacts. Since these slots are preferably quite narrow in order to facilitate the passage of the brush thereacross, it is preferred that at least two slots and preferably three be provided between each pair of stationary contacts 19. Such slots alone would help a great deal since, if a spark did occasionally pass across them, it would not transform the surface of the "Bakelite" within the slot and the slot would therefore maintain its insulating character. To increase the path that the current would have to follow along the walls of the slot, the deep ends of the slots preferably communicate with wells 54 which also serve a ventilating purpose, as is described below. It will be noted that the slots 53 are preferably slanting to facilitate the passage of the brush thereover. They will therefore communicate with one side of the wells 54 at their tops and with the other side of the wells 54 at their bottoms.

Considerable ozone is generated within the cavity 16. If this ozone is allowed to accumulate it reaches a degree of concentration which has a very strong oxidizing effect. This may corrode the contacts 18 and 19 and it may also increase the danger of flash-overs. According to the present invention the ozone is prevented from becoming concentrated by ventilating the cavity 16. In the form shown in Fig. 1 this ventilation is accomplished by providing passages 56 from some or all of the wells 54 outwardly and passages 57 opening into the cavity 16 at a position closer to the axis of rotation of the rotor 17. The rotating rotor 17 acts as a centrifugal pump or blower for blowing air out through the slots 53 and the passages 56 and drawing air in through passages 57. To increase the blowing effect the periphery of the rotor is preferably provided with relatively deep slots 58.

Although this distributor is designed primarily to be able to handle the currents and voltages of the circuit of Fig. 3, it may of course be used for the conventional ignition systems. To this end the bottom 26 of the coil housing will be supplanted by a simple terminal socket similar to the socket 33 for connecting the lead wire from the conventional coil directly to the contact 23. Inasmuch as it may sometimes be desirable to supply the distributors initially merely with the socket for the conventional ignition system and then to replace this socket with the housing shown in Fig. 1, having the booster unit therein, such socket may be threaded to the cap 59 of the distributor so that it may be unscrewed and the housing 27 with its bottom 26 screwed in in its place.

This construction has another very important advantage of facilitating the replacement of a booster if the winding 31 should prove imperfect and fail. Thus, the coil HF and its housing 26, 27 form a readily replaceable unit. This is particularly advantageous since the safeguards against flash-overs in cavity 16 leaves the wind-

ing 31 as the element most vulnerable to the high voltages carried.

The cap 59 may be secured to the body of the insulator housing 14 in any suitable manner as by the usual spring clips. Also, an annular recess 61 may be formed in one of these members with a corresponding rib in the other member with a gasket therebetween for sealing around the terminal socket 24.

Modified distributor and coil combinations 10

Figs. 5 and 6 illustrate a modified distributor and coil combination which is perhaps especially suitable for use in place of conventional distributor heads. The rotor 62, it will be observed, is provided with fins 63 for ventilating purposes (any suitable vents 65 being provided) and with an annular recess 64 for elongating the flash-over path between the brush 18 and the shaft 13. The distributor head or cap includes concentric grooves 66 and 67 for preventing flash-overs between the stationary contacts and ground or radial contacts 68 respectively. It is also provided with radial slots 69 and wells 70 corresponding to slots 53 and wells 54 of Figs. 1 and 2 for preventing flash-over between the stationary contacts. Furthermore, it has been illustrated as including hollow chambers 72 for receiving condensers 34 and 35 which would be connected to ground by suitable leads not shown.

In this instance the secondary winding 31 is sealed entirely within the distributor head or, more specifically, within the upward projection 76 thereon, being sealed therein by a pressed and impregnated fibrous bottom wall 77. It will be noted that the primary winding 28 is located outside of the housing extension 76 and hence there is no danger of a flash-over between the winding 31 and the leads to the winding 28 and, furthermore, no problem is presented with respect to perfect sealing of the leads for winding 28 in order to protect the winding 31. The leads for winding 31 are of course soldered into their respective terminal members so that they are effectively sealed.

The primary winding 28 is carried by a cap 79 which telescopes over the projecting portion 76. The winding 28 is sealed and insulated within the cap 79 by virtue of a plastic insulating compound 81 which is molded into place by a mandrel so that the cap 79 with the winding 28 therein will fit neatly over the projection 76. The leads 82 for the primary winding 28 may be soldered or otherwise sealed to terminal bushings 83 to which the condensers may be connected.

Referring to the arrangement of Fig. 8, the structure there shown employs a circuit arrangement similar to that of Fig. 3 but omitting the condenser 35 (although this condenser may be added if preferred). The high frequency booster transformer HF is made up as a unit with the distributor head in a one-piece housing 87. The housing supports the high frequency coil or transformer and also serves as the distributor cap. The housing 87 is provided with a top portion 88 which extends through a constricted neck 89 to a cap 91. In this embodiment of the invention the ordinary distributor cap may be entirely removed and housing 87 substituted therefor. The ordinary lead 92 to the center of the distributor head is simply inserted in an aperture in the top of the housing to engage one end of the secondary winding 31 (as is also true of Fig. 5). The other

end of the secondary winding is in electrical engagement with the distributor rotor 88.

Fig. 9 illustrates a construction similar to Fig. 8 except that the upper housing 88 is separable from the distributor cap 91 and in fact may simply be plugged into the conventional cap 91. Thus, to apply such a unit HF to an installation, the ordinary lead 92 to the center of the distributor head is removed. The terminal on one end of the housing 88, which is one terminal of the winding 31, is inserted into the distributor head and the removed terminal 92 then inserted in the top end of the housing 88 as seen in Fig. 8. The condenser ordinarily connected across the timer contacts 11, or a special condenser employed if desired, is connected in series with the primary winding 28 of the high frequency unit HF to provide the high frequency oscillating circuit. Of course, if it is desired to employ an extra kick coil for added output, such a coil is then suitably connected in circuit with the primary winding 28 as is indicated below in connection with Fig. 7.

Fig. 10 illustrates another modification wherein I provide a high frequency ignition system employing a one-piece housing 96 for supporting the high frequency transformer or coil HF. In this instance the coil is of the Odin type. The housing 96 serves as a cap for the distributor as in Fig. 8, or the two parts may be separable as in Fig. 9. The upper portion 97, closed at the top, supports the coil HF and extends through a constricted neck portion to the cap portion. The coil HF as a whole includes a primary winding 98 and a secondary winding 99, the circuits being seen best in Fig. 11. A kick coil 101 is utilized in this circuit as a source of energy for charging the condenser 102. The kick coil 101 under influence of the opening of the timer contacts 11 raises the voltage from the battery 41 to a high enough value to be effective. The primary high frequency oscillating circuit, it will be observed, includes the primary winding 98, the condenser 102 and the gap formed by the contacts 11. The winding 98 induces a high voltage in the winding 99 which boosts the voltage produced by coil 101.

The ordinary ignition coil in use at the present time is mounted on the dash-board with an extended cable lead to the distributor. With this installation there is a considerable energy loss in the secondary which in turn impairs the operating efficiency of the ignition system. However, in my system with the high frequency coil HF mounted directly on the distributor in the one-piece housing the secondary loss is negligible. Furthermore, this assembly provides for a short lead to the condenser 102 with the resulting shortest possible primary oscillating circuit. In this arrangement the low frequency transformer or kick coil 101 may be mounted at any desired distance from the distributor.

Employing the small high frequency coil HF mounted on the distributor in a one-piece combination housing and distributor cap provides a very inexpensive and sturdy unit. This unit operating in the straight high frequency circuit described, provides in all a highly efficient low cost ignition system.

Combination coil units

In some instances it will be desirable to apply the system of my invention to an internal combustion engine having a conventional ignition system. In these instances and perhaps in other instances it may be desirable to incorporate the high frequency unit in a single housing with the

conventional low frequency coil. This has some advantage in economy and perhaps may also have some advantage in inducing a unidirectional or low frequency voltage in the high frequency secondary coil as well as in the low frequency secondary coil.

In any of the forms the HF unit may have either a non-metallic or a comminuted iron core, and the latter may be especially valuable if this core is alined with and close to the core 108 of the LF unit. One convenient form of construction to this end is illustrated in Fig. 4. The main body of the housing may be in the form of a jar 106 which may be upright or inverted and which may have a preferably square recess 107 at its lower end for receiving the laminated iron core 108 of the low frequency coil. Around the core may first be wrapped the secondary winding 43 and thereafter the primary winding 42. A terminal 111 may be connected to both the primary and secondary windings, and a terminal 112 connected to the other end of the primary winding. The other end of the secondary winding will be connected to the secondary coil 31 of the high frequency unit HF.

The high frequency coil HF may be carried by a cap 113 which closes the open end of the housing 106. This cap may desirably be provided with a depending sleeve 114 for separating the secondary coil 31 from the primary winding 28 to prevent flash-overs between them. An inner cap 116 may be telescoped over the high frequency unit HF so as to insulate it thoroughly from the low frequency unit. On the lower side of the inner cap 116 a recess corresponding to the recess 107 may be formed to receive the upper end of the core 108. The secondary winding 31 may be wound on a tube (or comminuted iron core) which may be supported by suitable formations on the inside of the inner cap 116 and on the main cap 113. The terminal cap 113 is preferably provided with an elongated boss 118 which may have concentric grooves 119 formed thereon for elongating any surface flash-over path between output terminal 121 and any other terminals or supporting members of the combination coil unit. It may also be noted that the provision of the inwardly extending sleeve 114 and the inner cap 116 makes any internal flash-over paths quite long.

A similar form of the combination coil unit is shown in Fig. 7 which includes additional elements and may be somewhat simplified with respect to the HF coil housing. In this instance the main housing 126 is made large enough to contain the low frequency coil LF including the primary winding 42 and the secondary winding 43 and large enough to house in addition a kick coil 127 and condensers 34 and 35. In this instance the battery 41 may be connected to a terminal 128 which in turn may be connected to primary winding 42 and to kick winding 127. The other ends of both of these coils are connected to a terminal 129 which will of course be connected to the timer contacts. The terminal 129 will also be connected to condenser 35 which has another terminal 131 connected to ground, and to primary winding 28 of the high frequency unit HF, the other end of which is connected to condenser 34, which also has a terminal 131 connected to ground. The secondary winding 43 is connected at one end to the terminal 129 and at the other end to the secondary coil 31 of the high frequency unit. It will be understood of course

that the housing 126 may be filled with some insulating medium.

One advantage of the construction shown in Fig. 7 is the relative ease with which the various parts may be replaced. Thus, it is seen that the high frequency unit HF and each of the condensers 34 and 35 is supported by a housing member which is secured to a cap 132 by being threaded thereto. Hence, each of these units may be separately removed from the cap 132. As in Fig. 1, the HF booster unit including a housing of molded insulation is readily replaceable.

In Figs. 12 to 14 another modified form of the combination coil unit has been illustrated, one which, on the whole, is somewhat preferred because of its ease of manufacture as well as its satisfactory operation. The housing in this unit includes a base 136, a support partition 137, a plain cylindrical sleeve body portion 138, and a cap 139. The base 136 is provided with deep concentric grooves 141 to prevent flash-overs, particularly between its output terminal 142 and the supporting bracket which will normally be grounded and to which screws 143 may be secured. The support partition 137, which will be of molded and preferably fibrous insulating material, may be shaped as seen in Fig. 14 with an upper recess for receiving core 108 and a depending sleeve for receiving and insulating windings 28 and 31. The partition 137 is also preferably provided with peripheral apertures 146 to permit the insulating composition with which the entire housing is eventually filled to pass through from the sleeve 138 into the base 136. The cap 139 is preferably provided with a recess 147 to fit the upper end of the core 108. It is also provided with three terminals 149 for making the connections necessary in addition to the output terminal 142. A resistance unit 151 may conveniently be connected between two of these terminals and a fourth terminal on cap 139 and supported by them. Such a resistance is sometimes advantageous in the circuit of primary winding 42. It should also be mentioned that the connection between secondary windings 43 and 31 may be a bare, flexible, woven wire contacting core 108 as it passes through the partition or shelf 137.

Although winding 28, condenser 34 and contacts 11 form a high frequency oscillating circuit, it is not vital that this circuit have any particular high frequency. The winding 28 and condenser 34 and also the condenser 35 may therefore have a wide variety of values. It may be mentioned, however, that some values which have been found satisfactory are:

Condenser 34 _____ microfarad .1
Winding 28 _____ microhenry .413
Condenser 35 _____ microfarad .3

The value of the latter should of course be so chosen as to produce the proper interruption of current in the low frequency primary winding 42 when used in conjunction with winding 28 and condenser 34.

It is of course desirable that all of the housing members be formed of some suitable insulating material such as that known commercially as "Bakelite" whenever practical. It is obviously important that the various lead wires be thoroughly insulated from one another and from any grounding conductors. Likewise, it is to be understood that all of the coils will ordinarily be completely sealed and insulated from one another

by pouring a molten insulating compound into the housings. Such a compound will, upon solidifying, hold the various parts in proper positions.

From the foregoing it is seen that a variety 5 of forms of apparatus have been devised for handling the high frequency and high voltage generated by my ignition system or any other system for which such special apparatus may be suitable.

From the foregoing it is seen that a variety 5 of forms of apparatus have been devised for handling the high frequency and high voltage generated by my ignition system or any other system for which such special apparatus may be suitable. The disclosures of this application are illustrative and the invention is not to be limited by them. In fact, if modifications or improvements are not at once obvious, they may be devised in the course of time to make additional use of 15 the broad ideas taught and covered by this application. The claims are intended to point out novel features and not to limit the invention except as may be required by prior art.

I claim:

1. The combination of a low frequency ignition coil and a high frequency booster whereby very high voltages are produced having high frequency characteristics, and a distributor including a rotor and a housing therefor having a series 25 of contacts adapted to be connected by the rotor to the coil and booster, said rotor having peripheral formations for increasing the circulation of air thereby and said housing having vents whereby the rotor will cause air to circulate 30 through said housing to prevent the concentration of ozone therein.

2. The combination of a low frequency ignition coil and a high frequency booster whereby very high voltages are produced having high frequency 35 characteristics, and a distributor including a rotor and a housing therefor having a series of contacts adapted to be connected by the rotor to the coil and booster, said rotor having peripheral formations for increasing the circulation of air thereby 40 and said housing having vents whereby the rotor will cause air to circulate through said housing to prevent the concentration of ozone therein, said distributor also having grooves formed between the various contacts therein to elongate 45 the surface paths for flash-overs.

3. The combination of ignition spark means, a distributor and a high frequency booster unit including a housing having a distributor cavity therein, a rotor positioned in said cavity, a high 50 frequency secondary winding sealed within the housing and connected to the rotor, a high frequency primary winding in inductive relationship to the secondary winding, and a plurality of contacts within the distributor cavity adapted to be 55 connected with the ignition spark means for causing sparks in them.

4. The combination of ignition spark means, a distributor and a high frequency booster unit including a housing having a distributor cavity 60 therein, a rotor positioned in said cavity, a high frequency secondary winding sealed within the housing and connected to the rotor, a high frequency primary winding in inductive relationship to the secondary winding, a plurality of contacts within the distributor cavity adapted to be 65 connected with the ignition spark means for causing sparks in them, vents extending from the peripheral portion of the cavity outwardly, and air inlets opening at a more central portion of the 70 cavity.

5. The combination of ignition spark means, a distributor and a high frequency booster unit including a housing having a distributor cavity 75 therein, a rotor positioned in said cavity, a high

frequency secondary winding sealed within the housing and connected to the rotor, a high frequency primary winding in inductive relationship to the secondary winding, a plurality of contacts within the distributor cavity adapted to be connected with the ignition spark means for causing sparks in them, vents extending from the peripheral portion of the cavity outwardly, and air inlets opening at a more central portion 10 of the cavity, said rotor having peripheral projections thereon for acting as a centrifugal blower.

6. A distributor for distributing current to a plurality of ignition spark means, including a 15 housing having a distributor cavity therein, a rotor positioned in the cavity, a plurality of contacts within the distributor cavity adapted to be connected with the ignition spark means, vents extending from the peripheral portion of the 20 cavity outwardly, and air inlets opening at a more central portion of the cavity, said rotor being substantially circular in form and having a plurality of alternate projecting peripheral portions and depressed peripheral portions thereon for 25 acting as a centrifugal blower.

7. The combination of a distributor and a high frequency booster unit including a housing having a distributor cavity therein, a rotor and contacts positioned within said cavity, an extension carried by the housing and having a recess therein, completely sealed from the cavity and from the outside atmosphere, a high frequency secondary winding within the extension and connected to the rotor, and a high frequency primary winding 35 in inductive relationship with the secondary winding.

8. The combination of a distributor and a high frequency booster unit including a housing having a distributor cavity therein, a rotor and contacts positioned within said cavity, an extension carried by the housing and having a recess therein, completely sealed from the cavity and from the outside atmosphere, a high frequency secondary winding within the extension and connected 45 to the rotor, and a high frequency primary winding in inductive relationship with the secondary winding, and sealed within a removable cap telescoping over said extension.

9. The combination of a distributor and a high 50 frequency booster unit including a housing having a distributor cavity therein, a rotor and contacts positioned within said cavity, an extension carried by the housing and having a recess therein completely sealed from the cavity and from the 55 outside atmosphere, a high frequency secondary winding within the extension and connected to the rotor, and a high frequency primary winding in inductive relationship with the secondary winding, said extension being readily removable 60 from the housing whereby it may be readily interchangeable with other extensions.

10. The combination of a housing having a main body portion having an aperture therein, ignition apparatus within the main body portion, 65 and a replaceable unit including a separate casing molded of insulating material and separably supported by the main body portion as a closure for the aperture thereof, and a high frequency transformer including a secondary winding sealed 70 within the casing and connected with said apparatus, and a primary winding in inductive relation therewith.

11. The combination of a low frequency ignition coil and a high frequency booster including a 75 casing having a main body portion, a low fre-

quency ignition coil within the main body portion, an end portion closing off one end of the body portion, and a high frequency boosting unit sealed within the end portion and including primary and secondary windings, said end portion having an output terminal for the secondary winding separated from all external conducting parts by a projection of insulation, said projection being concentrically grooved to increase the length of flash-over path along the surface thereof from said terminal to any other conductor.

12. The combination of a low frequency ignition coil and a high frequency booster including a casing having a main body portion, a low frequency ignition coil within the main body portion, 15 an end portion closing off one end of the body portion, and a high frequency boosting unit sealed within the end portion and including primary and secondary windings, said end portion having an output terminal for the secondary 20 winding separated from all external conducting parts by a projection of insulation, said projection being concentrically grooved to increase the length of flash-over path along the surface thereof from said terminal to any other conductor, 25 said low frequency coil including an iron core and said high frequency secondary winding being inductively positioned with respect thereto.

13. The combination of a low frequency ignition coil and a high frequency booster including a casing having a main body portion, a low frequency ignition coil within the main body portion, an end portion closing off one end of the body portion, a high frequency boosting unit sealed within the end portion and including primary and secondary windings, said end portion having an output terminal for the secondary winding separated from all external conducting parts by a projection of insulation, 30 said projection being concentrically grooved to increase the length of flash-over path along the surface thereof from said terminal to any other conductor, 35 and an insulating partition between said end portion and said body portion supporting said low frequency coil thereon and said high frequency booster thereunder.

14. The combination of a low frequency ignition coil and a high frequency booster including a casing having a main body portion, a low frequency ignition coil within the main body portion, an end portion closing off one end of the body portion, a high frequency boosting unit sealed within the end portion and including primary and secondary windings, said end portion having an output terminal for the secondary 55 winding separated from all external conducting parts by a projection of insulation, said projection being concentrically grooved to increase the length of flash-over path along the surface thereof from said terminal to any other conductor, 60 and an insulating partition between said end portion and said body portion supporting said low frequency coil thereon and said high frequency booster thereunder, said partition having 65 passages formed therethrough to facilitate the filling of said body portion and said end portion with an insulating and sealing fluid.

15. As an accessory for amplifying the output of ignition systems having the usual spark coil, distributor head, timer contacts and condenser across the contacts, a high frequency oscillation coil unit having a supporting terminal end for insertion in the top of the distributor head for connecting one end of a secondary winding of the coil with the distributor arm and a second ter- 75

5 minal for connection with a terminal of a secondary winding of the spark coil, and a pair of leads on the unit for the primary winding for connection to the condenser and the timer contacts for providing the primary oscillating circuit for the high frequency coil.

10 16. In an ignition system having the usual distributor with timer contacts, rotor, and condenser across the contacts, a low frequency source of energy, a high frequency oscillating coil having a primary for connection with said low frequency source and said condenser and timer contacts, and a secondary for connection with the low frequency source and distributor rotor, and a combination coil housing and distributor cap fitting on said distributor for supporting said high frequency coil and covering said distributor and distributor rotor as the cap therefor.

15 17. In a distributor cap for the usual distributor for an ignition system, a hood-shaped lower portion and an integral top portion having a cavity therein for carrying an ignition coil having two high frequency windings and means in the cap for completing an electrical circuit from one winding of said coil to the rotor in the distributor, and means for completing a closed circuit from the other winding through the timer contacts in the distributor and a condenser.

20 18. An ignition unit including in combination a housing, a low-frequency coil unit within the housing at one end thereof, a high-frequency coil unit within said housing at the other end thereof including a secondary winding, an output terminal on the housing for the secondary winding

25 and available on the outside of said housing at said other end separated from all external conducting parts of said ignition unit by an insulating portion concentrically grooved to increase the length of flash-over path along the surface thereof from said terminal to any other conductor, a primary winding in said housing at said other end surrounding said primary winding and supported in inductive relation thereto, and an insulating partition in said housing between the 10 low-frequency coil unit and the high-frequency coil unit with said partition supporting either one coil unit or the other when the housing is standing in an upright position, with said partition being of such a configuration and acting in 15 such a manner as to maintain the supported coil unit in a relatively fixed position in said housing.

20 19. The combination in ignition apparatus of a distributor and a high-frequency coil unit including housing means with one portion of said housing means having a distributor cavity therein, a rotor and contacts positioned within said cavity, a second portion for said housing means separable from said first portion but fixedly connectible therewith, said second portion having a 25 recess therein, a high-frequency primary winding within said recess and in inductive relationship with the secondary winding, said primary winding having at least one end thereof adapted for connection to a condenser in the ignition apparatus to provide a primary oscillating circuit for the high-frequency coil unit.

HARRY B. HOLTHOUSE.
